UNITED STATES PATENT OFFICE.

MICHAEL HICKS, OF NEW YORK, N. Y.

CAR-LAMP.

SPECIFICATION forming part of Letters Patent No. 352,243, dated November 9, 1886.

Application filed October 23, 1885. Serial No. 180,759. (No model.)

To all whom it may concern:

Be it known that I, MICHAEL HICKS, a citizen of the United States, residing at the city of New York, in the county and State of New York, have invented certain new and useful Improvements in Lamps, of which the following is a specification.

My invention relates more particularly to lamps used in railway-cars; but it is also applicable to lamps in steamboats and other public places; and it consists of devices for holding the lamp-shade and securing and steadyng the upper portion of the lamp-chimney, my improved construction being such as to admit of the removal and replacement of the chimney without displacing or disturbing either lamp-shade or lamp-burner.

I have illustrated my invention by the accompanying drawings, in which Figure 1 is an elevation showing an upper section of a car-lamp having connected therewith my improvements. Fig. 2 is likewise an elevation representing the chimney-holding device thrown upward or disconnected from the chimney for the purpose of showing the springs which hold and steady the chimney when in its normal position. Fig. 3 is a detail showing one element of my invention, consisting of a clamping-screw which regulates the ring by means of which the shade of the lamp is supported and held in proper position. Fig. 4 is another detail showing a section of the cap or ring which encircles the top of the chimney, and with which the springs are connected, likewise showing the spring device, constituting a further element of my invention, which governs and controls the spring locking mechanism by which said cap or ring is held in position.

Like letters refer to like parts throughout the several views.

A indicates the supporting-frame of the lamp, secured to the roof B of the car in any suitable manner.

45 C indicates the lamp-shade.

D is a pipe extending through the ceiling of the car, through which the smoke and gases from the lamp escape.

E is that portion of the lamp which extends above the chimney and acts to convey upward the products of combustion in the direction of the upper pipe or ventilator, D.

b indicates the lamp-chimney.

c is the supporting-ring for the shade C.

c' is a circular spring fixed within the ring 55 c on one side by the nuts c" c'', passing through the ring c. On one side of the ring c and in a pocket or recess thereof is journaled the screw d, having a thumb-piece, e, the shaft of said screw having its two longitudinal halves screw-threaded in opposite directions, and fitting, respectively, into screw threaded holes in the two ends of the spring c'. The shade C is placed within the spring, and then the spring c' is tightened upon the shade by turning the 65 thumb-screw d in the proper direction and bringing the ends of spring c' toward each other. When it is desired to loosen the shade, the thumb-screw is turned in the opposite direction.

70 It will be observed that the screws c" c'' are screw-threaded only in the spring c', passing loosely through the ring c. This is to allow the necessary slide forward and back of the ring c, incident to its adjustment by the bolt d. 75

h is the chimney-supporting ring, to which or with which the springs k k are connected.

m indicates a coiled spring surrounding a bolt, the same being placed within the casing o, and together constituting the means for 80 holding the chimney-supporting ring h in position when hinged at one side, as shown in Fig. 2. The bolt referred to is indicated by x. When this ring is in its normal position, the bolt shown passes within a socket, from 85 which it is readily withdrawn by releasing the same from the pressure of the spring when it is desired to raise or remove said chimney supporting ring.

90 The special advantages of the construction constituting my invention consist in the readiness with which I am enabled to remove and replace the shade of the lamp, as well as the degree of security which is attained by holding such shade in the manner shown.

95 It not infrequently happens that lamp-shades are so loosely held in position that the motion of the car or steamboat tends to break the same, as well as to create a disagreeable rattling. My new construction both prevents 100 rattling and guards against any liability of the breaking of the lamp-shade. The further advantages are to be found in the means shown for permitting the raising of the chimney of

the lamp high enough to clear the burner, so that the chimney can be removed or replaced in the lamp without removing or disturbing either the lamp or the shade, and, still 5 further, in the use of the hinged cap described, having in connection therewith the springs shown, which springs act to steadily support the chimney when the cap is in position and prevent any motion or rattling.

10 The shade-holder is preferably attached by braces to the lamp-frame; but it may be entirely separated from the lamp and secured to the ceiling of the car, or otherwise supported.

15 The chimney-supporting ring, while preferably provided with springs *k k k*, such as shown in Fig. 2, may have other suitable appliances connected therewith, which will operate within said ring for securing and steady- 20 ing the upper portion of the lamp-chimney when in place. This chimney-supporting ring or cap I prefer to hinge to the shade-holder, as shown in Fig. 2; but it may be fitted separately and held in place by any suitable 25 means so as to be capable of being detached. When it is desired to release the chimney from the retaining action of the springs, it is only necessary to turn back or remove said ring in the manner indicated in 30 Fig. 2.

The operation of the construction which I have invented is as follows: When it is desired to either place in position or remove the lamp-shade, it is only necessary to open or 35 close the shade-supporting spring by means of the screw *d*.

I am aware that it has heretofore been proposed to mount that part of the lamp-frame carrying the shade and furnishing a support 40 for the chimney upon hinges, so that all that part of the lamp may be raised, if desired. This is a clumsy construction, since it is inconvenient to be compelled to raise the shade whenever it is desired merely to remove the 45 chimney, and I do not claim it. I, on the contrary, propose to hinge the chimney-supporting part of the frame immediately to that part which supports the shade, so that this alone need be moved when it is desired to lift the 50 chimney.

When it is desired to elevate the lamp-

chimney so as to raise the same far enough to clear the burner, it is only necessary to either lift or remove the chimney-supporting ring or cap so as to release the chimney from the 55 retaining force of the springs. The number of springs required for the office indicated is preferably three; but the number may be varied. The chimney-supporting ring or cap may be turned down when hinged or placed 60 in position when separately attached before the chimney is returned, or said chimney may be first placed in position and the supporting ring or cap either turned down or placed over the same. 65

Any person familiar with the construction of lamps will readily understand the material which will be best adapted for the parts which I have described and shown.

My improved construction has the merit of 70 cheapness, simplicity, and durability, and, while adding materially to the qualities required in a convenient and serviceable lamp, in no way detracts from the appearance of the same, but, to the contrary, is an addition thereto in the 75 respect last indicated.

Having thus described my invention, what I claim, and desire to secure by Letters Patent, is—

1. The combination, with the support of a 80 car-lamp, of the ring *c*, attached thereto, the chimney-supporting cap *h*, hinged to the said ring, the springs *k k k*, bolt *x*, and spring *m*, mounted on the cap *h*, substantially as described and shown. 85

2. The combination, with a car-lamp support, of a shade-holder attached thereto, and a chimney-supporting cap hinged to the shade-holder and provided with chimney-holding springs, substantially as described and shown. 90

3. The combination, in a shade-holder, of a circular spring for embracing the shade, the ends of said spring being provided with reversely screw-threaded holes, with a bolt provided at its two ends, respectively, with screw- 95 threads of opposite inclination and adapted to engage with the threads of the holes in the spring, substantially as described and shown.

MICHAEL HICKS.
